(57) CLAIM

The ornamental design for a food product, substantially as shown and described.

DESCRIPTION

FIG. 1 is a perspective view of a food product showing the new design.

FIG. 2 is a front view thereof.

FIG. 3 is a rear view thereof.

FIG. 4 is a right side view thereof.

FIG. 5 is a left side view thereof.

FIG. 6 is a top view thereof; and,

FIG. 7 is a bottom view thereof.

The broken lines shown in the drawings represent unclaimed portions of the food product and form no part of the claimed design.
